UNITED STATES PATENT OFFICE.

DONALD NOBLE, OF BRIDGEPORT, CONNECTICUT, ASSIGNOR TO THE SINGER MANUFACTURING COMPANY, A CORPORATION OF NEW JERSEY.

VARIABLE-SPEED POWER-TRANSMITTER FOR SEWING-MACHINES.

1,001,674.

Specification of Letters Patent. Patented Aug. 29, 1911.

Application filed May 17, 1907. Serial No. 374,189.

To all whom it may concern:

Be it known that I, DONALD NOBLE, a subject of the King of Great Britain, and a resident of Bridgeport, in the county of Fairfield and State of Connecticut, have invented certain new and useful Improvements in Variable-Speed Power-Transmitters for Sewing-Machines, of which the following is a specification.

10 My invention relates to improvements in speed controlling mechanism for sewing machines, and has for its object to effect an automatic change in speed through the power transmitting mechanism.

15 In the accompanying drawings illustrating the invention, in the several figures of which like parts are similarly designated, Figure 1 is a view in side elevation of a buttonhole sewing machine, power transmitter, and main driving shaft provided with pulleys, together with a sectional view of the power bench and the parts secured thereto. Fig. 2 is an enlarged rear end elevation of the sewing machine, transmitter,

20 table and table parts shown in Fig. 1. Fig. 3 is a rear side elevation of the sewing machine. Fig. 4 is a rear side view of the back end of the sewing machine, the bed-plate being shown in section, and the arm

25 standard shown partially in section to better illustrate the mechanism for controlling the cycle of feed movements of the material. Fig. 5 is an underside view of the sewing machine bed-plate and parts directly connected therewith. Fig. 6 is an enlarged central, vertical sectional elevation of the transmitter. Fig. 7 is a perspective view of the switch for manually controlling the transmission of power.

30 The machine to which my invention is in this case applied is commercially known as the "Singer buttonhole-sewing machine", but the invention is equally applicable to other forms of sewing machines constructed for cycle sewing, and in describing my invention only such limited reference will be made to the well-known parts of the sewing machine as is deemed necessary for a proper understanding of my invention.

35 1 is the bed-plate of the sewing machine, 2 the over-hanging arm, and 3 the arm standard.

40 4 is the work-holding and feeding clamp provided with a pivoted lever 5, one end of

which lever is connected by a chain 6 with a suitable foot treadle (not shown). The work-clamp 4 receives its cycle of feed movements through the step by step rotary movements of the feed disk 7 which is actuated from the main or needle-driving shaft 8 through connections comprising the eccentric 9 secured on said main shaft, and eccentric connection 10 connecting the eccentric 9 with a rock-shaft 11 mounted beneath the bed-plate 1, said rock-shaft being in turn connected by a feed adjusting link 12 with a lever 13 of the clutch device 14, which latter operates the feed disk 7 secured upon the lower end of a vertically arranged shaft 15 carrying a cam 16 later to be referred to, the upper end of said shaft being operatively connected with the needle vibrating mechanism (not shown) carried by the overhanging arm 2. For a more detailed understanding of the function of the feed disk and its actuating parts, reference may be had to U. S. Patent No. 784,291, March 7, 1905, to E. B. Allen.

The machine herein shown is provided with a stop-motion device comprising mainly a clutch controlling lever 17 carrying a spring actuated plunger 18, the upper end 19 of which co-operates with a stop cam 20 carried by the tight pulley 21 secured upon the main shaft 8, to stop the machine. Mounted upon the outer end of the shaft 8 is a loose pulley 22 over which a belt 23 travels when the machine is at rest, the tight pulley 21 coacting with said belt to drive the machine. The belt 23 is adjusted to coact with first one and then the other of the pulleys 21, 22 through a shipper lever 24 carried by the clutch controlling lever 17, a spring 25 acting, normally, to hold said controlling lever in the position shown in Figs. 1 and 3, or in the position which it occupies when the machine is at rest. Owing to the driven pulleys 21 and 22 rotating in a direction transverse to the rotation of their driving pulleys, an idler 23' is provided for the purpose of guiding the belt 23 in proper alinement with said driven pulleys.

Through connections comprising a rod 26, a chain 27 connected with a foot treadle (not shown), and an arm 28 forming a part of the lever 17, the upper end 19 of the plunger 18 is caused to be disengaged from the

notch 29 formed in the stop cam 20, and at the same time the lever 24 is moved to ship the belt 23 off the loose pulley 22 and into engagement with the tight pulley 21. To better facilitate the movements of the rod 26 in the direction of its length, the chain 27 is passed over and beneath suitable idlers 27', 28'.

30 is a bracket suitably secured to the rear 10 side of the arm standard 3 and provided with lugs 31, 32 into which are adjustably secured pintles 33, 33 upon which the clutch controlling lever 17 is pivoted.

The construction of the stop-motion device 15 vice above pointed out is substantially the same as is illustrated and described in U. S. Patent No. 738,591, Sept. 8, 1903, to E. B. Allen, to which reference may be had.

To the lower end of the clutch controlling 20 lever 17 is secured, by a stud bolt 34 and nut 35, a depending finger 36 to the lower end of which is hinged, by a stud screw 37 and nut 38, a latch 39 which is acted upon by a spring 40 to resiliently hold the hooked 25 end 41 of said latch against vertical movement.

42 is the transmitter bracket suitably secured to the underside of the work-bench 43 and provided with bearings 44, 45 in 30 which an upright shaft 46 is journaled, said shaft being held in its elevated position by a suitably secured collar 47. To the upper end of the shaft 46 is secured a collar 48 provided with an extended portion 48' to 35 which is secured an arm 49, the free end of which during the operation of the machine at its high speed is acted upon by the hooked end 41 of the latch 39, in a direction to cause the free end of an arm 50, secured to the 40 lower end of the shaft 46, to act upon the spring plunger 51 which forms a part of the power transmitting mechanism now to be described.

The transmitter comprises two casings 45 52 and 53, secured together at their outer edges by suitable screws 54, the casing 52 being secured by a screw 55 in a cylindrical bearing 56 formed in the lower end of the transmitter bracket 42.

50 57, 57 are hollow shafts mounted in the casings 52 and 53, one of said shafts carrying a low speed pulley 58 and the other shaft carrying a high speed pulley 59, the hubs 60 and 61 of said pulleys coacting with 55 suitable ball bearings 62 and 63 located in the oppositely arranged casings 52 and 53.

64 is a centrally mounted and frictionally driven machine belt driving pulley formed with oppositely arranged projecting hubs 60 65 and 66 mounted in the oppositely arranged hollow shafts 57, 57.

To the inner faces of the pulleys 58 and 59 are secured suitable friction rings 67 and 68 formed, in the present instance, of 65 leather, said pulleys acting to frictionally

drive the centrally mounted pulley 64 at different speeds.

69 and 70 are springs mounted in the hollow shafts 57, 57, the spring 69 being acted upon by the plunger 51, and the oppositely arranged spring 70 being confined between the adjusting screw 71 and ball bearing 72, which latter coacts with a hardened ring 73 mounted upon the end of the hub 66 of the pulley 64, the opposite hub 65 being provided with a like hardened ring and ball bearing located between the hub 65 and the spring 69.

74 is the main or power driving shaft 80 upon which are mounted the belt driving pulleys 75 and 76 of unlike diameters, the pulley 75 acting, through the belt 77, to drive the low speed pulley 58, and the pulley 76 acting, through the belt 78, to drive the high speed pulley 59, the belt pulley 64 being operatively connected, through the belt 23, with the tight and loose pulleys 21 and 22 mounted upon the main shaft 8 of the sewing machine.

In the operation of the machine, supposing the machine to be at rest with the parts in the positions shown in Figs. 3 and 5, the operator, through the foot treadle (not shown), pulls the rod 26 down until the notch 79 formed in said rod coacts with the end 80 of the catch lever 81 and holds said rod in its lowered position, and in doing so rocks the clutch controlling lever 17 to the position shown in Fig. 4, which causes the end 19 of the plunger 18 to be released from engagement with the notch 29 formed in the stop cam 20. At the same time the shipper lever 24 acts to ship the belt 23 off from the loose pulley 22 and onto the tight pulley 21, thus causing the machine to be put in operation for the overseaming of the buttonhole. As the feed disk 7 is about to complete its rotation in the overseaming of a buttonhole, a cam 82 carried by said disk contacts with a finger 83, which forms a part of the plate 84 adjustably secured to the catch lever 81, and withdraws the end 80 of said catch lever from the notch 79, thereby permitting the spring 25 to return the parts to their positions as shown in Fig. 3, and thus arresting the action of the machine.

In the operation of the speed controlling mechanism, supposing the machine to be at rest with the hooked end 41 of the latch 39 in its position for engaging the arm 49, as illustrated in Fig. 3, the oscillation of the clutch controlling lever 17 to its position for starting the machine in operation, as illustrated in Fig. 4, through the arm 49, causes the upright shaft 46 and the arm 50 carried by said shaft to turn in a direction to force the belt driving pulley 64 against the friction ring 68 carried by the fast driving pulley 59, through the connections comprising the plunger 51, spring 69, ball bear-

ing 72 and ring 73, thus, through the belt 23, transmitting to the machine its high speed.

During the operation of the machine for the overseaming of a buttonhole, the hooked end 85 of a trip lever 86 rides the cam 16 carried by the vertically arranged cam shaft 15, and just prior to the actuation of the stop-motion for arresting the action of the machine, said hooked end drops off from the point 87 of the cam 16, thus permitting the spring 86' to oscillate the lever 86 and, through a latch 88 pivotally secured at one end of the lever 86, and a pin 89, lift the latch 39 out of engagement with the arm 49, allowing the spring 70 mounted in the transmitter to force the belt pulley 64 into operative relationship with the slow driving pulley 58 and thus, through the belts 23 and 77, transmitting to the machine its low speed.

In the practical operation of machines of the character herein pointed out it is desirable, and in many cases essential, to discontinue for a time the action of the machine driving belt; and to effect this control of the power transmitting mechanism, I provide a manually controlled switch lever 90 which, in the present instance, is pivotally mounted upon a frame 91 secured by screws 92, 92 to the work-bench 43. The lever 90 comprises a main or hand adjusting portion and an L-shaped portion 93, the free end of the latter being provided with angular projections 94 and 95, the former acting as a stop or register for the arm 49 when the lever 90 is adjusted against the lug or stop 97, as shown in Figs. 3 and 7, or to the position which it occupies when the machine is at rest or when it is being actuated at its lowest speed. But when the lever 90 is adjusted against the stop or lug 96, the angular projection 95 acts to hold the arm 49 intermediate its positions for effecting the low and high speeds, thus, through the connections comprising the parts 46, 48, 50, 51, 69 and the duplicates of the ball bearing 63 and ring 73, causing the central belt pulley 64 to be held in a central position intermediate the pulleys 58 and 59, as illustrated in Fig. 6, thus holding the pulley 64 out of contact with the pulleys 58 and 59.

From the nature of the construction it is evident that the angular projection 94 for registering the arm 49 in its normal or low speed position might consist of an independently mounted part, as the use of such projection is simply a preferred form of construction.

Further, it will be understood that my invention comprehends a construction of speed controlling mechanism capable of use in connection with any of the forms of sewing machine construction which employ a cloth feeding mechanism automatically con-

trolled to effect a predetermined cycle of stitching, as distinguished from such earlier forms of construction of speed controlling mechanism as are so intimately connected with the control of the feed-actuating mechanism as to be limited to substantially the specific construction employed for arresting the action of the stitch-forming and cloth feeding mechanisms.

What I claim is:—

1. In a variable speed transmitter for sewing machines, a main driving shaft, a main power shaft, power transmitting pulleys mounted independently of said shafts, said power transmitting pulleys including an adjustably mounted and frictionally driven machine belt driving pulley, and connections for transmitting power from said main power shaft through said power transmitting pulley to the main driving shaft, in combination with automatic means for effecting a reduction in the speed of the sewing machine at a predetermined time.

2. In a variable speed power transmitter for sewing machines, a main power shaft, driving pulleys mounted on said shaft, an adjustably mounted and frictionally driven machine belt driving pulley, two positively driven pulleys mounted to rotate on the same axis as said frictionally driven pulley, said frictionally driven pulley being arranged intermediate said positively driven pulleys, in combination with means for adjusting and yieldingly holding said frictionally driven pulley in operative relationship with either one of the other of said positively driven pulley including springs mounted on opposite sides of said adjustably mounted and frictionally driven machine belt-driving pulley.

3. In a variable speed power transmitter for sewing machines, a main power shaft, driving pulleys mounted on said shaft, a frame or casing, three pulleys journaled in said frame, two of which are positively driven at different speeds and arranged on opposite sides of the third or adjustably mounted and frictionally driven machine belt driving pulley, in combination with automatic means for effecting a yieldingly controlled operative engagement between said frictionally driven pulley and the positively driven pulley of slowest speed.

4. In a variable speed power transmitter for sewing machines, a main power shaft, driving pulleys mounted on said shaft, a casing, a multiple of pulleys mounted to rotate upon the same axis journaled in said casing, two of which are positively driven at different speeds and arranged on opposite sides of the third, the latter frictionally driven and acted upon by oppositely arranged springs, in combination with manually operated means for adjusting and hold-

ing said frictionally driven pulley out of operative relationship with said positively driven pulleys.

5. In a variable speed power transmitter for sewing machines, a main power shaft, driving pulleys mounted on said shaft, a two-part frame or casing, hollow shafts secured in said frame, positively driven power transmitting pulleys journaled upon said 10 shafts, and an adjustably mounted and frictionally driven machine belt driving pulley journaled within said hollow shafts, in combination with means, including springs, for resiliently holding said frictionally driven 15 pulley in operative relationship with either one or the other of said positively driven pulleys.

6. In a variable speed power transmitter for sewing machines, the following instrumentalities in combination: an adjustably 20

mounted and frictionally driven machine belt driving pulley, positively driven pulleys mounted upon the same axis and arranged on opposite sides of said machine belt driving pulley, said positively driven pulleys 25 provided with devices for frictionally driving said machine belt driving pulley, a spring mounted to move said machine belt driving pulley in one direction, a spring actuated to move said machine belt driving 30 pulley in the opposite direction, and a plunger for actuating said last named spring.

Signed at Bridgeport, in the county of Fairfield, and State of Connecticut, this 10th 35 day of May, A. D. 1907.

DONALD NOBLE.

Witnesses:

ALBERT K. WILLIAMS,
ABBIE M. DONIHEE.
